UNITED STATES PATENT OFFICE.

EMIL PEDRAZZO, OF GUTTENBERG, AND MARIUS TUA, OF UNION CITY, NEW JERSEY.

PRINTING MACHINE.

Application filed October 23, 1925. Serial No. 64,328.

This invention relates to printing means for printing ornamental designs or indicia on tubular articles preferably of the fabric type and more specifically to means for printing suitable designs upon hosiery and gloves.

Attempts have been made to weave ornamental designs in hosiery; but this method renders the articles too costly for general commercial purposes, therefore efforts have 10 been made towards printing, stamping or stenciling the required designs upon such articles. However, owing to the extreme flexibility and the tubular configuration of hosiery and the like, much difficulty has been 15 experienced in the practical application of these methods.

An object of this invention is to provide means for conveniently applying articles of hosiery and the like to a suitable roller or 20 mandrel and then automatically conveying the rollers to printing positions after which the rollers are automatically conveyed to discharge or release positions.

Another object of this invention is to provide an improved printing form of the roller or mandrel type which is constructed for 25 quickly receiving and securing the article to be printed thereto and including means for automatically cooperating with the conveying components of the machine to effect 30 the conveyance of the article to printing position.

A further object of this invention is to provide novel conveying means for conveying 35 the printing roller through the various operating phases of the machine, the conveying means including automatic means for gripping the roller at its initial position and for automatically releasing the roller at the 40 end of its printing operation.

In printing the highly ornate designs now commercially required on women's hosiery it is necessary to provide and apply a number of different colors or pigments; and it 45 is an object of this invention to provide a printing mechanism comprising a number of separate units and arranged so that the required number of units may be incorporated in a machine for printing a specific 50 design, certain of the units including inde-

pendent color or pigment applying means so that as many coloring units may be incorporated in the machine as there are different colors to be applied.

An additional object of this invention is 55 to effect the accurate positioning or registration of the printing roller relative to the conveying and printing means to insure accurate printing of the design upon the desired portion of the article to be printed.

It is also an object of this invention to provide a hosiery printing machine of generally improved construction, whereby the device will be simple, durable and relatively inexpensive in construction, as well as convenient, practical, serviceable and efficient in 60 its use.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 70 within the scope of what is claimed, without departing from the spirit of the invention.

The invention has been illustrated in its preferred embodiments in the accompanying drawings, wherein:

Figure 1 is a plan view of the invention, parts being broken away, and depicting only one of the printing units;

Figure 2 is a diagrammatic elevation of the machine showing a number of printing units;

Figure 3 is a side elevation of the device, parts being broken away;

Figure 4 is a vertical transverse sectional view taken on a line 4-4 of Figure 1;

Figure 5 is a fragmental elevation of the 90 printing roller or mandrel, parts appearing in section;

Figure 6 is a perspective view of one of the printing units;

Figures 7 and 8 are detail elevation views 95 showing different operating phases of the conveyor hooks; and

Figure 9 is a perspective view of a stocking showing an ornamental design printed thereon.

Referring to the drawings, in which corresponding parts are indicated by similar reference characters, there is shown a composite supporting frame 10 comprising separate units which are bolted or otherwise secured together as indicated at 11. The opposed end or frame units 12 and 13 are arranged to support the conveying mechanism, the unit 13 including spaced bearing pedestals 14 in which a longitudinally disposed shaft 15 is journaled. The shaft 15 has a worm 16 rigidly secured thereto and positioned between the bearings of the pedestals 14, and the outer end of the shaft has a gear 17 secured thereto, which gear meshes with a pinion 18 driven by a suitable motor 19. A shaft 22 extends transversely across the frame unit 13 and is journaled in the side walls of this unit. Sprockets 23 are secured to the opposed ends of the shaft 22, and suitable conveyor chains 24 are trained around and guided by the sprockets. Motion is imparted to the shaft 22 by a gear 25 secured to the shaft intermediate its ends, which gear, in turn, meshes with and is driven by the worm 16. The opposed terminal unit 12 has a transverse shaft 30 journaled in the side walls thereof and this shaft operably supports spaced sprockets 31 around which the chains 24 are trained.

Each intermediate frame unit 32 is constructed to receive and support a printing unit 33, and each printing unit is positioned between spaced lugs or ears 34 formed on the intermediate frame unit 32. Set screws 35 are threaded through the ears 34 and engage the printing unit thereby rigidly securing each printing unit to its supporting frame, and each printing unit 33 can be vertically adjusted by means of adjusting screws 36. The number of printing units employed in each machine is determined by the nature of the design to be printed, therefore if only one color is required, one printing unit will suffice; but in multi-colored designs as many printing units may be employed as there are colors to be applied. Each printing unit or pad is provided with a hollow casing 40 to which the coloring matter is conveyed from a suitable reservoir, not shown, and the supply of pigment or coloring matter may be regulated by a suitable valve 41. Designs or stencil apertures 42 are formed in the upper wall or face 43 of the printing unit, which apertures are shaped to conform to the configuration of the design which is to be stamped upon the article to be printed. The coloring matter, through suitable means, not shown, finds its way into the design aperture 42. This means for supplying the coloring matter to the design aperture and for controlling the level of the coloring matter in proper relation to the printing unit is to be made the

subject matter of a separate patent application, therefore need not be further elucidated herein.

Detachable rollers or mandrel units 45 are provided to receive and support the stocking S or article to be printed. Each mandrel unit comprises a hollow frusto-conical roller or body member 46 which is peripherally reduced intermediate its ends, as indicated at 47, to receive a covering member 48 which is preferably formed of rubber or any suitable porous material such as porous porcelain and the like. The small end of the roller 46 has a recess 46a formed therein to receive the foot of the stocking, and then the leg portion of the stocking is stretched over the roller covering 48, thereby conforming to the configuration of the roller. After the stocking has been so positioned on the roller, a clamping head 49 is placed on the small end of the roller so that the inner wall 50 of the cylindrical clamping head will tightly engage the stocking when the clamping devices 51 have been turned to locking position, thus firmly securing the stocking to the small end of the roller and at the same time rigidly securing the clamping head thereto. A stub shaft 52 extends longitudinally from the clamping head 49 and this shaft has a lantern gear 53 rigidly secured thereto, while the outer end of the shaft is reduced to receive the inner ring 54 of an anti-friction ball bearing device. The anti-friction balls 55 operably support an annulus 56 which has a concave annular recess 57 formed in the periphery thereof, the annulus 56 being so supported that a slight lateral motion of the annulus relative to its supporting shaft 52 is permitted, and the bearing unit is locked to the shaft 52 by suitable nuts 58. A stub shaft 60 extends axially from the large end of the roller 46 and this shaft also carries a lantern gear 61 and bearing unit 62 similar to those which are carried by the shaft 52. The large end of the roller is provided with a short cylindrical portion 63 which cooperates with the inner wall 64 of a clamping ring 65 that is loosely supported upon the shaft 60. After the stocking has been properly positioned upon the roller 46 the top edge of the stocking will surround the cylindrical portion 63 of the roller and then the clamping ring 65 is slipped over the large end of the roller and securely clamped to the roller by means of the clamping bolts 66, thereby clamping the top of the stocking to the large end of the roller.

Opposed racks 70 and 71 are supported by brackets 72 carried at the upper edge of the supporting frame units. These racks extend horizontally along the supporting frame units from a point adjacent the left end of the machine to a point beyond the remote outer edge of the last printing unit

away from the left end of the machine. From this point the racks are inclined, as indicated at 73, and lead to suitable terminal supporting frames or rails 74 positioned 5 at the extreme right end of the machine.

The conveyor chains 24 are provided with conveying members or hooks which are positioned at predetermined and regular intervals along the chain. Each hook 75 includes a bifurcated body portion which straddles and is pivotally secured to the chain 24, as indicated at 76. An arcuate slot 78 is formed in the portion 76 and is arranged in concentric relation with respect 10 to the pivot or fulcrum pin 77, and a suitable stop pin 79 is secured to the chain and is positioned within the arcuate slot 78 thereby limiting the movement of the hook plate 76 about its pivot 77. One terminal 15 of a helical retractile spring 80 is secured to the lower end of the plate 76 while the other end of the spring is secured to an ear 81 carried by the chain 24. An arcuate neck 82 extends upwardly from the plate 76, 20 the inner edge of the neck or hook 82 being shaped to conform to the shape of the peripheral groove 57 formed in the outer rings of the anti-friction bearings. The hook members are normally held in their upright 25 position by the action of the spring 80 and by the stop pins 79; but in order to move these hooks about their fulcrum pins 77 to a receiving position, as indicated in Figure 8, there are provided two sets of guide cams 30 85 which are carried by the supporting frame units and are positioned in the normal path of travel of anti-friction rollers 86 which are journalled to the plates 76. Each cam 85 has an inclined surface 87 35 formed thereon which engages the roller during predetermined phases of operation of the machine thereby moving the hooks to receiving position and releasing positions.

In operation, an operator can position the 40 stockings or articles to be printed upon the rollers and then each roller is placed upon the racks 70 and 71 in such a position that the index mark 90 which is inscribed on the shafts 60 and 52 will register with the index arrow or finger 91 supported by the frame unit. This arrangement insures the proper 45 positioning of the roller upon the racks so that the design will be printed accurately upon the stocking. After the roller has 50 been so positioned it remains there until the hook members 75 grip the bearing rings 56 and convey the rollers along the horizontal portions of the racks. As the rollers move 55 along the racks the stocking is pressed against the upper face 43 of the respective printing units thereby causing the selected 60 designs to be printed or stamped upon the stocking. When the multi-color design is required one color is imparted to the stocking 65 by the first engaged printing unit, and

as each additional unit is engaged additional colors may be applied to the proper portion of the design. After the printing units have been passed, the hooks disengage the rollers by the action of the herein- 70 before described cams 85 and then the roller can move by gravity down the inclined portions 73 of the racks to the delivery or supporting rails 74 from which point the rollers may be removed from the machine and the 75 stocking in turn removed from the roller.

Having thus described our invention what we claim is:

1. In combination, in a printing machine of the character described, a stationary 80 printing unit, a detachable mandrel constructed to securely support the article to be printed, conveying means, means for automatically securing the mandrel to the conveying means, thereby permitting the 85 conveying means to convey the mandrel to and in rolling contact with the printing unit, and means for automatically detaching the mandrel from the conveying means.

2. In combination, in a printing machine 90 of the character described, a printing unit, a detachable mandrel, means for rigidly securing the article to be printed upon the mandrel, conveying means, means carried by the conveying means for automatically 95 securing the mandrel to the conveying means, thereby causing the conveying means to convey the mandrel to and in rolling contact with the printing unit, and means for automatically releasing the mandrel from the conveying means. 100

3. In combination, in a printing machine of the character described, a printing unit, a detachable mandrel constructed to rigidly support the article to be printed, flexible 105 conveying means, means for driving the conveying means, hook members carried by the conveying means for operably securing the mandrel to the conveying means, and means positioned in the path of travel of 110 the said hooks for automatically moving the hooks to engaging position, and means cooperating with the hooks for yieldingly securing the hooks to the mandrel.

4. In combination, in a printing machine 115 of the character described, a printing unit, a detachable mandrel constructed to securely support the article to be printed, a flexible conveyor, hook members pivotally secured to the conveyor and normally held in gripping position, cam members positioned in the path of travel of the hook members and constructed to move the hook members to mandrel receiving position, thereby causing 120 the hooks to operably engage and secure the mandrel to the flexible conveyor, and cam members positioned in the path of travel of the hook members and constructed to move the hook members from engagement with the mandrel. 125

5. A mandrel for use in printing machines including a body member adapted to receive the article to be printed, means co-operating with the opposed ends of the body member for clamping the article to be printed upon the body member.

6. A mandrel for use in printing machines including a body member having an aperture formed in one end thereof, said 10 mandrel adapted to receive the leg portion

of a stocking thereon, the foot portion of the stocking being received by the said aperture, clamping means cooperating with the opposed ends of the body member for clamping the stocking to the body member.

Signed at Guttenberg, in the county of Hudson and State of New Jersey, this 17th day of October, 1925.

EMIL PEDRAZZO.
MARIUS TUA.
